UNITED STATES PATENT OFFICE.

EUGENE FULLER, OF ARCTIC CENTER, RHODE ISLAND.

ELECTRIC FIRE-ALARM APPARATUS.

No. 797,424.

Specification of Letters Patent.

Patented Aug. 15, 1905.

Application filed January 28, 1905. Serial No. 243,125.

To all whom it may concern:

Be it known that I, EUGENE FULLER, a citizen of the United States, residing at Arctic Center, in the county of Kent and State of Rhode Island, have invented new and useful Improvements in Electric Fire-Alarm Apparatus, of which the following is a specification.

My invention pertains to electric fire-alarm apparatus, and its novelty, utility, and practical advantages will be fully understood from the following description and claims when taken in connection with the accompanying drawing, forming part of this specification, in which the figure is a view illustrating in perspective and diagrammatically the apparatus constituting the present and preferred embodiment of my invention.

Referring by letter to the said drawing, A is a support, preferably a board, designed to carry certain of the elements of my apparatus which are to be located at the central station of a fire-alarm system.

B B are contact-pieces suitably supported on the board A and arranged in a normally open electric circuit C, together with a source of electric energy D and an incandescent lamp E or other suitable annunciator. The said contact-pieces B are preferably of the construction illustrated—*i. e.*, respectively comprise spring portions *a*, the upper ends of which diverge, as illustrated, for a purpose presently set forth.

F F are electromagnets also mounted on the board A and disposed above the contact-pieces B, and G is an armature, preferably a swinging armature, disposed and movable vertically between the contact-pieces and the electromagnets and having knives or bars *b*; arranged to seat in the contact-pieces. The contact-pieces B in practice are made sufficiently strong to hold the armature G against the power of the current supplied to the electromagnets F, this with a view of precluding the current being casually cut off from the annunciator E after the annunciator has been made active to apprise those in interest of a fire-alarm, as will be presently more fully described.

The electromagnets F are arranged in a normally closed circuit H, together with a source of electric energy I and one or more switches J, the said switches being designed to be arranged in fire-alarm boxes or at alarm-stations.

By virtue of the construction thus far de-

scribed it will be apparent that with the parts in the positions illustrated a person desiring to turn in an alarm has simply to move the lever of the switch J from the position shown in full lines to that shown in dotted lines, since when this is done the electromagnets F will be disengaged, thereby releasing the armature G, the bars *b* of which will fall into the contact-pieces B and by so doing will close the electric circuit C and make active the lamp or other annunciator E. The switch J is designed to be closed immediately after the sending in of an alarm; but this will not operate to break the electric circuit C and extinguish the lamp E, for the reason that the spring contact-pieces B will hold the armature against the pull exerted by the energization of the magnets F, as before mentioned. From this it follows that after the lamp E is made active to indicate a fire-alarm the armature G must be raised by hand or by extraneous means in order to break the electric circuit C and extinguish the said lamp.

The armature G may be returned to the position illustrated to break the electric circuit C by a person located at the fire-alarm box or at any other remote point through the medium of a switch K, an auxiliary circuit L, and certain devices appurtenant to said circuit, and may also be returned to the position illustrated at a predetermined time through the medium of a clock M, arranged in a second auxiliary circuit N, together with the appurtenant devices mentioned. In addition to the switch K the auxiliary circuit L includes a source of electric energy P, while in addition to the clock M the auxiliary circuit N includes a source of electric energy Q. The appurtenant devices mentioned are electromagnets R, an armature S, and a cable T, passed over a sheave U and connecting the upper end of the armature S and the outer end of the armature G complementary to the electromagnets F. By virtue of this construction it will be observed that when the switch K of the auxiliary circuit L is closed current will pass from one pole of the source of electric energy P through the electromagnets R and back to the other pole of the source of energy, and hence the armature S will be attracted to the electromagnets, and the armature G will be drawn upwardly out of engagement with the contact-pieces B and placed under the influence of the electromagnets F. Immediately subsequent to the completion of the auxiliary circuit L

and the consequent interruption of the circuit C the circuit L is interrupted by opening the switch K, so as to prevent the armature S from interfering with the gravitation of the armature G when another alarm is sent in.

The auxiliary circuit N and the appurtenances thereof are utilized when it is desired to interrupt the circuit C and extinguish the lamp E at a predetermined time subsequent to the sending in of a fire-alarm. To so utilize the said auxiliary circuit N and the appurtenances thereof, the clock M is set so that at the predetermined time a contact-piece c, connected to one wire of the circuit, will be moved by the clock mechanism into engagement with a contact-piece d, connected electrically with the other wire of the circuit. With the said contact made it will be apparent that the auxiliary circuit N will be complete, and the consequent energization of the electromagnets R will operate to attract the armature S and raise the armature G to the position illustrated.

It will be gathered from the foregoing that my novel apparatus is at once simple and inexpensive in construction and reliable in operation and that it embodies no parts likely to become deranged after a short period of use.

I have specifically described the construction and relative arrangement of the parts embraced in the present and preferred embodiment of my invention in order to impart a full, clear, and exact understanding of the said embodiment. I do not desire, however, to be understood as confining myself to the said specific construction and relative arrangement of parts, as such changes or modifications may be made in practice as fairly fall within the scope of my invention as claimed.

Having described my invention, what I claim, and desire to secure by Letters Patent, is—

1. In an electric fire-alarm apparatus, the combination of a normally closed electric circuit, means whereby said circuit may be opened, a normally open electric circuit containing an annunciator, means for closing the second-mentioned circuit when the first-mentioned circuit is opened, a normally open electric circuit containing an electromagnet, an armature controlled by the electromagnet and connected with and arranged to return to its normal position the means for closing the second-mentioned circuit when the first-mentioned circuit is opened, and a clock for clos-

ing the circuit in which the last-mentioned magnet is arranged at a predetermined time.

2. In an electric fire-alarm apparatus, the combination of a normally closed electric circuit, means for opening and closing said circuit, a normally open electric circuit containing an annunciator, means for closing the second-mentioned circuit when the first-mentioned circuit is opened, a normally open auxiliary electric circuit, means for closing the auxiliary circuit, and means operated by the closing of the auxiliary circuit for returning the means for closing the second-mentioned circuit when the first-mentioned circuit is opened to its normal position.

3. In an electric fire-alarm apparatus, the combination of an electromagnet arranged in a normally closed electric circuit, means whereby said circuit may be opened, an annunciator and a contact-piece arranged in a normally open electric circuit, an armature movable between the electromagnet and the contact-piece and arranged when in engagement with the latter to complete the second-mentioned circuit, an electromagnet arranged in a normally open auxiliary electric circuit, a clock for closing said auxiliary circuit at a predetermined time, and an armature complementary to the second-mentioned electromagnet and mechanically connected with the first-mentioned armature.

4. In an electric fire-alarm apparatus, the combination of an electromagnet arranged in a normally closed electric circuit, means whereby said circuit may be opened and closed, an annunciator and a contact-piece arranged in a normally open electric circuit, an armature movable between the electromagnet and the contact-piece and arranged when in engagement with the latter to complete the second-mentioned circuit, an electromagnet arranged in a normally open auxiliary electric circuit, means for closing said circuit, an armature complementary to the second-mentioned electromagnet, a sheave, and a cable passed over the sheave and connecting the two armatures.

In testimony whereof I have hereunto set my hand in presence of two subscribing witnesses.

EUGENE FULLER.
